L'Inventor

G. L. E. KLINGBEIL,

By Samuel Henick,

Attorney,

UNITED STATES PATENT OFFICE.

GOTTLIEB L. E. KLINGBEIL, OF OMAHA, NEBRASKA.

SPRING SPREADER.

Application filed December 30, 1924. Serial No. 758,849.

To all whom it may concern:

Be it known that I, GOTTLIEB L. E. KLINGBEIL, a citizen of the United States, residing at Omaha, in the county of Douglas and State of Nebraska, have invented certain new and useful Improvements in Spring Spreaders, of which the following is a specification.

This invention relates to spring spreaders somewhat of the type disclosed in my co-pending application Serial Number 715,444, filed May 23, 1924.

It is one of the objects of the present invention to provide a hand-operated tool of the character shown in the accompanying drawing, constructed in such manner that the wedge carrying block with the bank wedges mounted therein may be bodily removed as a unit and a corresponding block with a bank of wedges therein, substituted for the same, in a very facile way. The utility of this arrangement will be manifest when it is remembered that the garageman is called upon to take care of cars of many different types, with springs having leaves of varying thicknesses and widths. In most cars the front springs differ in thickness from the rear springs. By the use of the present invention, springs of many different sizes and kinds may be expeditiously treated with lubricant.

Further objects and advantages of the invention will be set forth in the detailed description which follows:

35 In the accompanying drawings:

Figure 1 is a side view of a spring spreader constructed in accordance with the invention;

Fig. 2 is an edge view thereof;

40 Fig. 3 is a longitudinal sectional view through the structure on line 3—3 of Fig. 1;

Fig. 4 is a transverse sectional view upon line 4—4 of Fig. 1;

Fig. 5 is a detail edge view of an end plate hereinafter described;

Fig. 6 is a face view of the end plate;

Fig. 7 is a perspective view of a modified form of wedge retaining means;

50 Fig. 8 is a perspective view of one of the wedges;

Fig. 9 is a perspective view of a modified form of wedge; and

Fig. 10 is a perspective view of a rubber cushioning block hereinafter described.

55 Like numerals designate corresponding

parts throughout the several figures of the drawing.

The device of the present invention comprises a supporting frame consisting of a pair of rods 5 and 6 which are held in proper relation to each other by a cross-bar 7. The rods 5 and 6 are adapted to have wedge plates 8 and 9, a follower plate 10, carrying a handling extension 10^a and an end plate 11, mounted upon them. When both of these wedge plates 8 and 9 are to be employed the end plate 11 is not used. However, there are times when it is desired to use only one wedge plate, as, for example, where the spring lies so close to some other part of the vehicle that it is not convenient to get a wedge plate therebehind. Therefore it is to be understood that the tool as used, comprises, under some conditions, the two wedge plates 8 and 9 as illustrated in Fig. 1 and under other conditions comprises only the wedge plate 9, with the end plate 11 substituted for the wedge plate 8.

The wedge plates 8 and 9 are provided with slotted portions 12, 12^a at one end and arcuate slots 13, 13^a at their opposite ends, to adapt these plates to be removed laterally from the rods 5 and 6. Thus, it is not necessary to remove the nuts from the bolts 5 and 6 but, upon the contrary, either of the plates 8 and 9 or both of them may be removed by disengaging the hooked ends 17 thereof from the corresponding rod and then slipping the other and slotted end thereof out of engagement with the opposite rod. By virtue of this construction I am able to readily substitute one wedge carrying plate for another to take care of the particular type of automobile being operated upon. Where the leaves of the springs of the automobile are thicker in one case than in another, I may readily substitute wedge carrying plates having thicker wedges so that the points of the wedges will aline with the spaces between the spring leaves. Furthermore, the hook like part 17 permits the outermost wedge plate to be swung to one side during the time that the tool is being adjusted in position about the spring. To lock the plates 8, 9 and 11 in their position of engagement upon the tool I provide thumb screws 18, 18^a and 18^b and it is clear that until these screws are retracted, the wedge carrying plates cannot be disengaged from the rods 5 and 6. A power screw 19

is threaded in bar 7 and serves to force the follower plate 10 and consequently the wedge plate 9, with its associated bank of wedges 20, forcibly toward the bank of wedges 21, carried by the wedge plate 9, said wedges being caused to enter in unison and forcibly between the several leaves of the spring to separate said leaves and to permit the insertion of lubricant therebetween. The wedges 20 and 21 are held in position within the wedge plates by providing them with substantially T shaped shanks 22, the stems of which lie in relatively narrow slots 23 formed in the wedge plates while their heads 24 lie in somewhat wider slots formed in said wedge plates. To hold the banks of wedges against undue separation with respect to each other while at the same time permitting a limited yielding of the wedges longitudinally of the wedge plate to permit them to seek the most advantageous position in entering between the leaves of the springs, rubber filling blocks 24 are provided, said filling blocks having relatively narrow portions 25 adapted to lie within the slot 23 at the opposite ends of the banks of wedges and somewhat wider heads 26 which lie within the wider portions 25' of the slot of the wedge plates. Thus, as long as these rubber filling blocks are in position the wedges are so held that they extend transversely with respect to the wedge plates but with either of the rubber filling blocks removed, the wedges may be moved freely in the slotted portions of the wedge plate and may be turned in longitudinal alignment with said plates to disengage said heads from said plates and consequently permit the ready removal of said wedges.

To render the filling blocks more elastic they are preferably provided with a row of openings 27, though these may be omitted if desired. In Fig. 7, I have illustrated a modified way of holding the wedges against turning with respect to the wedge plates, this method being utilized, when desired, in lieu of employing the rubber filling blocks. In said Fig. 7, the wedge plate 8^a carries wedges 21^a and shims 21^x which wedges comprise T shape bodies consisting of the shanks 21^b and heads 21^c, which leaves in effect, slots 21^d at the opposite sides of the wedges and shims and which slots receive the ribs 30 of the wedge plate 8^a. A wire 31 extends longitudinally through openings 32 formed in the several wedges and shims to thereby hold these elements against turning. Thus these wedges cannot move from a position of transverse alignment with respect to the wedge plates, to a position of longitudinal alignment and consequently there is no danger that they will fall out of the wedge plates. The shims may or may not be used, as desired. They are not nec-

essary when the wedge plates are rendered interchangeable as in Fig. 1, for example. The wedge plates 8 and 9 are provided with ribs 33 and 34 respectively (see Fig. 1), which correspond with ribs designated 34^a in Fig. 7 and the follower plate 10 is provided with a rib or extension 35 adapted to enter between said ribs of the wedge plate which happens to be disposed adjacent thereto. This aids in preventing accidental transverse dislodgment of the wedge plate 9 even after the screw 18^a is loosened. The operating screw 19 is provided with an angular head 19^a for engagement by a wrench or other tool. It is provided with a rounded end 19^b, which engages in a correspondingly shaped recess, formed in the follower plate 10. The provision of the handle 10^a upon the follower plate 10 provides means for manipulating the tool during the time that it is being placed in position with respect to the spring.

It is to be understood that the invention is not limited to the precise construction set forth but that it includes within its purview whatever changes fairly come within either the terms or the spirit of the appended claims.

Having described my invention, what I claim is:

1. A device of the character described comprising a pair of rods, a cross-bar connecting said rods, a screw threaded in the cross-bar, a follower plate slidable upon the rods with which said screw is engaged, a wedge plate, a bank of wedges floatingly mounted therein, interengaging means between the back of the wedge plate and the face of the follower plate, and a backing plate opposed to the wedges of the wedge plate.

2. A structure as recited in claim 1, wherein the backing plate is separable by a lateral movement from one of the rods to permit of the passage of the rods over a spring.

3. In a tool of the character described, a wedge plate, a bank of wedges therein engageable with respect thereto and being removable therefrom by being turned to a longitudinal position with respect thereto, and filling blocks between said wedges and said plates to prevent turning movement of the wedges with respect to the plates.

4. In a tool of the character described, a wedge plate, a bank of wedges therein engageable with respect thereto and being removable therefrom by being turned to a longitudinal position with respect thereto, and elastic filling blocks between said wedges and said plates to prevent turning movement of the wedges with respect to the plates.

5. In a tool of the character described, a plate having an elongated slot formed

- therethrough, one part of which is wider than another, a plurality of wedges having slotted edge portions adapted to engage in the said slot and removable therefrom by being turned to positions of longitudinal alinement with respect thereto, and rubber filling blocks adapted to fit within said slot of the plate to hold the wedges against turning movement.
6. A structure as recited in claim 1, wherein said plate has a longitudinally slotted portion at one end and a hooked portion at the other end.
7. A structure as recited in claim 1, wherein said plate is provided with a lon-
- gitudinally slotted portion at one end, a hooked portion at the other end, and means carried by said hooked portion for preventing lateral movement of the plate.
8. A structure as recited in claim 1, wherein said plate is provided with a longitudinally extending slotted portion at one end, a hooked portion at the other end, and a threaded element traversing the hooked portion, to prevent lateral swinging movement of the plate until said threaded element is retracted.

In testimony whereof I affix my signature.

GOTTLIEB L. E. KLINGBEIL.
